United States Patent Office

Des. 208,529
Patented Sept. 12, 1967

208,529

VACUUM CLEANER

Harold J. Schoettler, Newport Beach, Calif.
(3303 W. Beverly Blvd., Montebello, Calif. 90640)

Filed Nov. 14, 1966, Ser. No. 4,643

Term of patent 14 years

(Cl. D9—2)

Fig. 2.

FIG. 1 is a perspective view showing the left side and rear, and the top of a vacuum cleaner embodying my new design; and

FIG. 2 is a perspective view showing the right side and front, and the top of the vacuum cleaner.

I claim:

The ornamental design for a vacuum cleaner, substantially as shown.
